DISPENSER FOR STAPLES OR THE LIKE

Alexander J. Kirby, Detroit, Mich.

Application December 12, 1945, Serial No. 634,455

11 Claims. (Cl. 232—42)

1

This invention relates to dispensers, and more particularly to dispensers for articles of U-shape such as staples or the like.

An object of the invention is to provide a dispenser which may be conveniently carried by the wearer and from which the articles to be dispensed may be readily withdrawn for use.

A further object of the invention is to provide a dispenser wherein the articles to be dispensed are maintained in stacked relation and from which they may be withdrawn individually in position for instant use.

A further object of the invention is to provide a dispenser which may be suspended from the user's clothing, and having means for retaining the articles in the dispenser if the dispenser is inverted or carelessly handled.

A further object of the invention is to provide a dispenser wherein the articles are retained in predetermined arrangement by their own weight and from which the lowermost article may be withdrawn by a single movement of the user's hand.

A further object of the invention is to provide a dispenser which shall be simple in construction and operation and economical to manufacture.

Further objects and advantages of the invention will be apparent from the following description, taken in connection with the appended drawing, in which:

Fig. 1 is a view in side elevation of a dispenser embodying the invention;

Fig. 2 is a sectional view of the same taken on the line 2—2 of Fig. 1;

Fig. 3 is a bottom view of the dispenser;

Fig. 4 is a front view of the lower portion thereof; and

Fig. 5 is a rear view of the upper portion thereof.

It is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

The dispenser shown in the drawings comprises an inner shell 10 of U-shape to conform to the shape of the articles to be dispensed, which are shown in the drawings as being staples 12 of the type commonly used for securing electrical wiring or the like in place on a wall. The shell 10 is formed with outturned vertical flanges 14. Concentric with the shell 10 is an outer shell or casing 16, spaced from the shell 10 to form therebetween a channel 18 U-shaped in cross section. The shell 16 is provided with outturned vertical flanges 20 which overlie the flanges 14 and are

2

secured thereto by means of a back plate 22 having its edges turned over to embrace the outer edges of the flanges 14 and 20. The elements 10, 16 and 22 are preferably formed as steel stampings. Secured to the outer shell is a wire 24, which may be soldered or welded into place, and which is bent to form a hook 26 adapted to engage a strap or similar member 28, which may be the user's belt.

10 The upper end of the outer shell 16 terminates below the upper end of the inner shell 10, to facilitate charging the dispenser with the articles to be dispensed. Secured to the forward face of the shell 10, by welding or soldering or the like, is a detent 30 the outer edge of which substantially coincides with the forward edge of the outer shell, and is formed with a downwardly extending lip 32 the purpose of which is to retain the upper articles in place and thereby prevent their falling out of the dispenser when the same is inverted, as will happen through accident or when the dispenser is thrown down after use.

At its lower end, the inner shell 10 is formed with integral outturned flanges 34 which extend 20 horizontally across the space between the inner and outer shells to form a closure or support for the articles stacked in the dispenser. Extending from the bottom of the shell 10 is an integral cam 36 having its forward end extending forwardly 30 slightly beyond the forward surface of the outer shell 16 and upturned so that when the lowermost article is withdrawn from the stack by a horizontal pull, the article will be forced by cam action to move upwardly. Accidental or unintentional 35 displacement of staples from the dispenser is in this manner prevented.

The lower forward portion of the outer shell is cut away as indicated at 38, to expose a sufficient area to enable the user to grasp the lowermost 40 article between his thumb and forefinger and exert a horizontal pull thereon for the purpose of withdrawing the same from the dispenser. This movement will preferably be a quick one, so that the inertia of the dispenser will cause it to 45 remain in vertical position while the article is being withdrawn. Forwardly of the opening indicated at 38 a lip 40 extends downwardly to within a short distance of the cam 36, the vertical distance between the two elements being slightly 50 greater than the vertical dimension of one of the articles to be dispensed. The lip 40, however, terminates at a point inwardly of the cam 36.

As a result of the construction above described, the dispenser may be charged by inserting articles 55 horizontally between the lower end of lip 32 and the upper surface of the outer shell 16, each article falling into place in the stack thus formed in the channel 18. If the dispenser is then inverted, the uppermost article will be prevented 60 by lip 32 from falling out of the dispenser.

In the use of the device, the operator grasps the lowermost article between his thumb and forefinger and jerks or draws it quickly in the horizontal direction forwardly of the dispenser. The cam 36 imparts an upward movement to the article as it is being withdrawn, so that its lower forward edge rides upwardly on the cam, while its upper forward edge clears the lip 40, its position when being withdrawn being indicated at 42 in Fig. 1. The remainder of the articles in the stack then drop to contact the flanges 34, while the user has the withdrawn staple grasped in such position that it is ready to be driven into the wall or other surface where it is to be used.

Although the invention has been described with particular reference to a specific form thereof, it may be embodied in other forms within the skill of artisans in this art, and is therefore not limited to the form disclosed, nor otherwise except in accordance with the terms of the following claims.

I claim:

1. In a dispenser for staples or like articles, concentric inner and outer shells spaced from each other to form a channel to receive said articles in stacked relation, a closure for the lower end of said channel, the outer shell being cut away to permit the lowermost article to be grasped and withdrawn, and a cam formed on said closure to force said article to move upwardly while being withdrawn.

2. In a dispenser for U-shaped articles, a vertical guide member, an outer shell spaced from the guide member to form a U-shaped channel therebetween to receive said articles in stacked relation, a closure for the lower end of said channel, the lower portion of the outer shell being cut away to form an opening to permit the lowermost article in the stack to be grasped and withdrawn horizontally from the stack, and a cam formed on said closure to cause said article to move upwardly while being so withdrawn.

3. The invention defined in claim 2, comprising in addition a tongue extending across a portion of said opening and cooperating with said cam to prevent discharge of said articles through said opening by gravity.

4. The invention defined in claim 2, comprising in addition a detent at the upper end of said channel positioned to engage and retain the uppermost article in the stack to prevent discharge thereof when the dispenser is inverted.

5. In a dispenser for U-shaped articles, concentric inner and outer guide members spaced from each other to form a vertical U-shaped channel to receive said articles in stacked relation, a closure for the lower end of said channel, the lower portion of the outer guide member being cut away to form an opening to permit an article in the stack to be grasped and withdrawn from the stack, and a cam associated with said closure to cause said article to move upwardly while being so withdrawn.

6. A dispenser for U-shaped articles comprising a vertical guide member, an outer container spaced from the guide member to form a U-shaped channel therebetween to receive said articles in stacked relation, a retaining member obstructing the lower end of said channel, the lower portion of the container being cut away to form an opening to permit the lowermost article in the stack to be withdrawn therefrom by a horizontal force, and a cam associated with said retaining member and shaped to cause said article to move upwardly while being so withdrawn.

7. A dispenser for U-shaped articles comprising inner and outer guide members spaced from each other to form a U-shaped channel to receive said articles in stacked relation, a retaining member for the lower end of said channel, the lower forward portion of the outer shell being cut away to form an opening to permit an article to be withdrawn from the stack by horizontal force, a cam secured to the inner guide member and shaped to cause said article to move upwardly while being so withdrawn, and a detent extending across a portion of said opening and spaced from said cam member to prevent an article from being withdrawn from the stack by gravity.

8. The invention defined in claim 7, wherein the outer guide member terminates below the upper end of the inner guide member, and the inner guide member is provided with a detent cooperating with the outer guide member to permit articles to be charged into the channel while preventing their movement out of the dispenser by gravity.

9. In a dispenser, vertical inner and outer guide members spaced from each other to form a channel therebetween to receive in stacked relation articles to be dispensed, retaining means at the lower end of said channel, the forward lower portion of the outer guide member being cut away to partially expose the lowermost articles, a vertically extending lip projecting from the outer guide member partially across said opening to prevent displacement of the articles from the dispenser by gravity, and a cam member extending forwardly of said opening to impart vertical movement to an article being withdrawn through said opening.

10. A dispenser for staples or like articles, comprising an inner vertical guide member U-shaped in cross section and formed with outwardly extending vertical flanges, an outer vertical guide member U-shaped in cross section and spaced from the inner guide member to form therebetween a vertical U-shaped article-receiving channel, flanges formed on the outer guide member and engaging said vertical flanges to retain the articles in the channel, the forward lower portion of the outer guide member being formed with an opening to expose the lowermost of said articles, a lip formed on the outer guide member and extending downwardly partially across said opening to prevent displacement of said articles from the channel by gravity, and a cam member formed on one of the guide members and extending forwardly and upwardly from the base of said opening to impart vertical movement to an article being withdrawn through said opening.

11. The invention defined in claim 10, wherein the outer guide member terminates below the upper end of the inner guide member, and the inner guide member is provided adjacent its upper end with a detent cooperating with the outer guide member to permit articles to be charged into the channel while preventing their movement out of the dispenser by gravity when the dispenser is inverted.
